UNITED STATES PATENT OFFICE.

JOHN B. CHARPIOT, OF HOUSTON, TEXAS.

DESIGN FOR A HATCHET OR AX HEAD.

SPECIFICATION forming part of Design No. 30,736, dated May 9, 1899.

Application filed March 13, 1899. Serial No. 708,982. Term of patent 14 years.

To all whom it may concern:

Be it known that I, JOHN B. CHARPIOT, a citizen of the United States, residing at Houston, in the county of Harris and State of Texas, have invented and produced a new and original Design for Hatchet or Ax Heads; and I do hereby declare the following to be a full, clear, and exact description of the same, reference being had to the accompanying drawings, forming a part thereof.

This invention relates to a new and original design in hatchet or ax heads and is embodied in the features hereinafter described and disclosed in the accompanying drawings, in which—

Figure 1 is an elevation showing one side of the head. Fig. 2 is an elevation showing the reverse side. Fig. 3 is an elevation showing one end.

As represented in the drawings, the upper edge of the head is generally formed of a substantially straight line A, running from the rear end of the head a distance of approximately one-third the length of the head, from which point the edge is curved, as shown at B, and from the end of the curve B it extends in an upward curve C to the front vertical edge D of the head. In the front face of the head at the upper edge is a wide notch or groove E, which gradually tapers down to a substantially straight vertical slot e in the rear face of the head. The front and rear faces along the line A and first portion of the curved line B are chamfered or beveled off, as shown at F. The lower edge of the head has a substantially straight portion G below the straight portion A, which does not extend to the rear end of the head. From the rear end of the portion G the edge extends on an inclined right line downwardly and rearwardly to the vertical rear edge H of the head, form-

ing a depending substantially wedge-shaped claw. From the forward end of the substantially straight portion G and opposite the curved portion B the lower edge is curved reversely to the curved portion B, as at H', and from the forward portion or end of the portion H' the edge curves downwardly and outwardly to the front vertical edge D. In the lower edge are two substantially V-shaped slots I and J, the latter of which is substantially vertically under the notch E in the upper edge. The front vertical edge of the head is chamfered or beveled off, as indicated at d. The rear or reverse side of the head is substantially the same in all respects with the front face, as described, with the exception above mentioned, that instead of the slot or groove E there appears on this face the short substantially vertical narrow slot e. The rear face of the claw is provided with a long substantially V-shaped slot K, as shown in Fig. 3.

The essential features of the design are the general configuration of the head, as described, showing the depending substantially wedge-shaped claw, the upper edge provided with the groove or notch E on one side tapering to a narrow slot e on the other side, and the two slots I and J and the substantially V-shaped slot K in the claw.

Having thus described the invention, what I claim as new, and desire to secure by Letters Patent, is—

The design for a hatchet or ax head, substantially as shown and described.

In testimony whereof I affix my signature in presence of two witnesses.

JOHN B. CHARPIOT.
